UNITED STATES PATENT OFFICE.

JOSEPH J. WALSER AND HARLAND FANKBONER, OF CHICAGO, ILLINOIS, ASSIGNEES
TO GOSS PRINTING PRESS COMPANY, A CORPORATION OF ILLINOIS.

CAM MECHANISM.

Original application filed June 18, 1917, Serial No. 175,403. Divided and this application filed January 29, 1920, Serial No. 354,981.

The invention relates to cam mechanism, and such a mechanism is exemplified herein as part of the inking mechanism of a printing press, although it will be understood that 5 cam mechanism constructed in accordance with the invention is capable of use in other mechanisms and mechanical relations as well.

Objects and advantages of the invention 10 will be set forth in part hereinafter, and in part will be obvious herefrom, or may be learned through practice with the invention; the same being attained through the means, instrumentalities and combinations pointed 15 out in the appended claims.

The invention consists in the novel parts, constructions, arrangements, combinations and improvements herein shown and described.

20 This application is a division of our pending application Ser. No. 175,408, filed June 18, 1917.

The accompanying drawings, referred to herein and constituting a part hereof, illustrate one embodiment of the invention, and together with the description, serve to explain the principles of the invention.

Of the drawings:—

Fig. 1 is a fragmentary elevation of the 30 inking mechanism and associated parts of a printing press and show a cam mechanism embodying the invention;

Fig. 2 is a fragmentary elevation looking at Fig. 1 from the left;

Fig. 3 is a fragmentary detail elevation, 35 with parts in section of the cam mechanism in the lower right hand corner of Fig. 1, looking thereat from the right; and

Fig. 4 is a sectional detail view, on an 40 enlarged scale, taken on line 4-4 of Fig. 1.

Referring to the accompanying drawings, 45 illustrating by way of example, one embodiment of the invention, the impression cylinder of a rotary printing couple is indicated by 1, the shaft 2 thereof being mounted in suitable bearings 3, carried upon the press frame. A cooperating form cylinder 4 has its shaft 5 mounted in like bearings 6, also carried upon the machine frame. The web 50 α is run between the cylinders of the printing couple and is printed in the usual manner.

Referring to the illustrated embodiment of the inking mechanism, a ductor roller is

provided cooperating with a plurality of 55 ink fountain rollers, one ink fountain roller preferably, cooperating, with the ductor roller on either side thereof. Also, the ductor roller cooperates with a plurality of ink drums, and preferably the ductor roller 60 engages with one ink drum on either side thereof, the ductor roller at one end of its travel engaging with the two ink fountain rollers on either side thereof to receive the ink, and at the other end of its travel engaging 65 with the two ink drums to deliver the ink thereto, the ink being delivered to the form inking rollers which ink the plates on the cylinder.

In accordance with one feature of the invention, a plurality of form rollers are provided, one of the form rollers receiving its ink more directly from the source of ink supply than the other, and more particularly, in accordance with said feature of the 70 invention, there is an additional ink drum interposed between one of the form rollers and the source of ink supply, such additional ink drum receiving its ink from the 75 other form roller.

According to one feature of the invention, also, there are a plurality of ink drums 80 cooperating with a single form inking roller to impart ink thereto, and preferably an ink drum runs in contact with such form roller 85 on either side thereof.

In the embodied form, these various features of invention are associated together in a single mechanism, together with other features of invention, which will be later described and pointed out. In the embodied form the ductor roller cooperates with two fountain rollers, one at either side thereof, both of which supply ink to the ductor roller. At the other end of its travel, the ductor 90 roller engages with two ink drums, one at either side thereof, to both of which ink drums the ductor roller imparts a supply of ink. These two ink drums impart ink to one form inking roller, which roller in turn supplies ink to the plates upon the form cylinder, and also to an additional ink drum, which last mentioned ink drum supplies ink to another form inking roller, which roller inks the plates upon the form cylinder.

In accordance with one feature of the invention, a vibrating, frictionally driven metal roller also cooperates with one of the

form rollers to mix and distribute the ink thereon preparatory to applying it to the plates upon the form cylinder.

Associated with the foregoing are other novel features of invention, many of which are designed to assist in rendering most highly efficient the action of the instrumentalities and mechanisms already pointed out.

Referring in more detail to the illustrated embodiment one or more ink fountains are provided, and as shown there are two such fountains. In the ink fountain 10 is a fountain roller 11, which is intermittently rotated while cooperating with the ductor roller, in the usual manner. The actuating means for the ductor roller may be of any suitable or adequate form, and as illustrated herein a shaft 12 is carried in suitable brackets 13 mounted on the machine frame, and carried on shaft 12 is a cam 14. Cooperating with the cam 14 is a longitudinally-reciprocating rack bar 15, and carried by said rack bar 15 is a cam roller 16, which roller cooperates with the cam 14. The cam roller 16 is fixed to the bar 15 in a suitable manner, as by a bolt 17. The rack bar 15 has fixed thereto at 18 a longitudinally extending guide rod 19, which guide rod works in a guiding aperture in the brackets or lugs 20 fixed to the machine frame.

Thus as the shaft 12 rotates, rack bar 15 and guiding rod 19 are vertically reciprocated (Fig. 1).

Rack bar 15 is provided with a series of teeth 21, which teeth mesh with a toothed sector 22 carried loosely upon a shaft 23. A roller 24 is mounted in the bracket 20, and bears against the back of the rod 15 to hold it to its work. Fixed to reciprocate with the geared sector 22 is a pawl lever 25 provided with a pawl 26. The pawl 26 cooperates with a ratchet wheel 28, which ratchet wheel is fixed upon the shaft 23 of the fountain ink roller 11. Thus as the rack bar 15 reciprocates, the pawl 26 is oscillated to and fro, thereby imparting intermittent rotary movement to the ink fountain roller 11 when the ductor roller is in contact therewith. Suitable means for varying the throw or travel of the pawl 26 are provided, but are omitted from the drawings for the sake of clearness, together with other details of the associated mechanism.

In the embodied form a second ink fountain roller 31 also supplies ink to the ductor roller and is preferably located in a separate ink fountain 30. Fountain roller 31 is intermittently rotated, like the fountain roller 11, while the ductor roller is in engagement therewith. Suitable mechanism is provided for this purpose and if desired may be similar to that already described in connection with fountain roller 11, but the showing thereof is omitted from the drawings for the sake of clearness.

The ductor roller 32 is carried in suitable bearings in a pair of arms 33, which arms are fixed to a shaft 34 mounted in and extending transversely to the frame of the machine. Fixed to the shaft 34 is an arm 35, and pivotally connected to the end of the arm 35 is a link 36. The other end of the link 36 is pivotally connected to a bell crank lever 37, which lever is pivotally mounted at 38 on the machine frame. Bell crank lever 37 at its other end is provided with a cam roller 39, which roller cooperates with a suitable cam mechanism, to be later described, whereby the ductor roller is traveled to and fro between the fountain rollers 11 and 31 and the two ink drums to which the ductor roller delivers its ink.

Means are provided by the invention for regulating and adjusting both the position and the travel of the ductor roller to compensate for shrinkage in the size of the roller, and to compensate for variations in size due to replacement of an old roller by a new, and to regulate the pressure or contact of the ductor roller with each of the respective fountain rollers, and also with each of the respective ink drums. In the embodied form of such means, the ductor roller 32 is mounted to have adjustment longitudinally in its bearings in the arms 33. For this purpose, the pintles 40 of the roller 32 are carried in slots 41 formed in the ends of the arms 33.

Means are also provided for regulating or varying the extent of travel of the ductor roller, and the exact location of the termini of its travel, to compensate for shrinkage and for variation in the size of new and old ductor rollers, as already explained. In the embodied form of such means, the pivotal connection of the link 36 with the bell crank lever 37 is adjustable to vary the effective throw of the lever. As embodied, a slot 48 is formed in the end of the lever 37 whereby the pivotal bearing 38' may be moved backwardly and forwardly in the slot, thus increasing or decreasing the throw of the arm 33, and thereby correspondingly varying and regulating the travel of the ductor roller 32. Adjusting means are also provided in the link 36, such as a turn buckle 49, whereby the length of the link 36 may be slightly varied to regulate the terminal points of the travel of the ductor roller, and to effect a smooth and harmonious action of the mechanism.

Means are also provided by the invention, in connection with the actuating means for the ductor roller, for regulating and varying the dwell of the ductor roller, both at the fountain ink rollers and at the ink drums. In accordance with certain features of the invention, such regulating means or devices are operable or regulable independently of each other.

In the embodied form of such actuating and regulating means, there is fixed to the shaft 12 a cam 55 having a cam groove 56 formed therein. In the groove 56 operates a cam roller 57, fixed to an arm 58, which arm is fixed to a shaft 62. Fixed also to the shaft 62 is an arm or plate 60, whereon is carried a plurality of cooperating, but independently positionable cams, which cams, through roller 39 and lever 37, actuate the ductor roller 32.

As embodied, there is formed in the arm or plate 60 a slot 61, through which slot projects a tap-bolt 63, the tap-bolt being threaded into a cam 64, which cam is fulcrumed on the shaft 62 (see especially Fig. 4). The roller 39 runs upon the periphery of the cam 64 (see Figs. 1 and 3) and determines the length of the dwell of the ductor roller against the ink fountain rollers. Also fulcrumed upon the shaft 62 is a cam 68, the upper portion 69 thereof being bent over the outer or operative edge of the cam 64 (Figs. 3, 4 and 5), whereby the part 69 is brought into position to cooperate with the cam roller 39.

In the plate 60 is formed a slot 70, through which slot projects a tap-bolt 71, which tap-bolt is threaded into the cam 68. A spacing block 72 encircles the tap-bolt 71 and is located in a slot 74 in the cam 64 and between the plate 60 and the cam 68, to prevent jamming and clamping of the cam 64 by the bolt 71. The cam 68 regulates the dwell of the ductor roller 32 against the ink drums, and by reason of the cams 64 and 68 being independently positionable, the dwell of the ductor roller at the fountain rollers and of the ink drums may be regulated independently of each other, as may be desired or required for the best results in any particular case.

From the foregoing it will be seen or understood that means are provided whereby not only the periods of dwell of the ductor roller at the fountain rollers and also at the ink drums are regulated as desired, but the extent of travel of the ductor roller, the precise positioning of the termini of its path of travel, and the time and force of contact with each of the fountain rollers, and also with each of the ink drums, is adjusted and regulated as may be desired or required for the most efficient and adequate inking in any particular case or for any particular work.

In accordance with features of the invention already referred to, an ink drum 76 and an ink drum 77 are provided engaging with the ductor roller 32 at either side thereof, as shown in dotted lines in Fig. 1. Both the ink drum 76 and the ink drum 77 cooperate with the form inking roller 78, which form inking roller supplies ink to the plates upon the form cylinder 4 and also to an ink

drum 79, which ink drum also rotates in contact with the form roller 78. Cooperating with the ink drum 79 is a form inking roller 80, which likewise supplies ink to the plates on form cylinder 40.

Cooperating with the form roller 78 is a smooth metal roller 81 running frictionally in contact with the form roller 78 and adapted to assist in the distribution of the ink on the form roller.

The ink drums 76, 77 and 79 and the roller 81, in the preferred form, are all vibrated, and the ink drums 76, 77 and 79 are likewise positively driven, while the roller 81 is frictionally driven from form roller 78. In the embodied form of vibrating means, there is fixed on the shaft 12 an eccentric 86, the strap 87 thereof being connected to a rod 88. The rod 88 is pivotally connected to an arm 89, which arm is fixed to a shaft 90 journaled in a bracket 91 mounted upon the machine frame.

Fixed to the shaft 90 is an arm 92, provided with a roller 93, which roller runs in an annularly grooved collar 94 formed upon the shaft 95 of ink drum 77. The ink drum is positively rotated from the other end of its shaft, as will be later described. An arm 97 extends upwardly from the shaft 90 and is provided with a roller 98, said roller working in an annularly grooved collar 99 carried on the shaft 100 of the frictionally driven roller 81.

Fixed to shaft 90 is a geared sector 104, with which meshes a geared sector 105, fixed to a shaft 106, which shaft is journaled in a bracket 107 carried on the machine frame. From shaft 106 an arm 108 extends downwardly and is provided with a roller 109, said roller working in an annularly grooved collar 110 on the shaft 111 of the ink drum 76. The ink drum 76 is likewise positively driven from the other end of its shaft, as will be later described. From the shaft 106 an arm 114 extends upwardly and carries a roller 115, said roller working in an annularly grooved collar 116 on the shaft 117 of the ink drum 79, which ink drum, like the others, is driven from the other end of its shaft.

By reason of the two fountain rollers cooperating to ink the ductor roller, the ductor roller receives a large and adequate supply of ink, its entire surface being practically covered with a layer of ink, of the requisite thickness and very evenly distributed, in the short time that the ductor roller is in contact with the fountain rollers. The ductor roller being completely supplied with ink as described, comes in contact with both the cooperating ink drums and the ink is transferred thereto, and is then transferred by both the ink drums to the first form inking roller.

The first form inking roller, this being the

form roller which the forms first encounter as they come round from the impression, thus receives an adequate supply of evenly distributed ink for the first, and also for the 5 subsequent inking of the plate. As hereinbefore described the second form inking roller is supplied preferably from the first form inking roller. The vibrating distributing roller 81, running in contact with the first 10 form inking roller, assists in providing and maintaining a constant and even distribution of the supply of fresh ink.

The first form inking roller, carrying fresher ink than the second form inking 15 roller, and making contact with the plates on the form cylinder ahead of the second form inking roller, prevents the lint or dust from the paper being picked up by the inking mechanism, as would be the case if a 20 comparatively dryer and more sticky form roller should come in contact with the plates immediately after they have left the impression. A very rapid and efficient speed control for the ductor roller is also effective.

25 By reason of the ductor roller cooperating with the two fountain rollers, and being as it were pressed or wedged therebetween, the ductor roller is immediately brought down from the high speed at which it was 30 spinning or rotating after leaving the ink drums and almost at once is brought to the slow speed of the fountain rollers, which would not be the case if the ductor roller made contact with only one fountain roller. 35 Furthermore, when the ductor roller, at the other end of its travel, engages in like manner with the two ink drums it will be practically immediately brought up from the comparatively slow speed of the ink fountain rollers to the speed of the ink drums, 40 which likewise would not be the case if but a single ink drum were used.

Thus there is secured a much better and 45 more quickly acting control of the ductor roller on a high speed press, in which the inking mechanism is likewise highly speeded, than would be otherwise possible. There is also insured an adequate supply of ink for fast running presses, and this supply 50 very fully and uniformly distributed to the various devices.

Other objects and uses of the invention will be understood by those skilled in the art or may be ascertained by practice with 55 the invention. It will be understood that changes may be made from the exact construction shown and described without departing from the principles of the invention and without sacrificing its chief advantages.

60 What we claim is:—

1. A cam mechanism including in combination a cam body, a pivoted mounting therefor, a high and a low part carried thereby and each being independently position-

able to vary the operation of the cam, and a 65 cam for actuating the first mentioned cam.

2. A cam mechanism including in combination a cam body, a pivoted mounting therefor, a high and a low part carried thereby and each being independently positionable to vary the operation of the cam, 70 and a rotary cam for actuating the first mentioned cam.

3. A cam mechanism including in combination a rotating cam having a fixed cam 75 path, an oscillating cam operated thereby and having an adjustable cam path to vary the throw of the oscillating cam.

4. A cam mechanism including in combination a rotating cam having a fixed cam 80 path, an oscillating cam operated thereby, a member cooperating with said oscillating cam, said oscillating cam having an adjustable cam path to vary the dwell of said oscillating cam with respect to said member 85 cooperating therewith.

5. A cam comprising a pivot bearing, an actuating arm extending in one direction from the pivot, and a flat body plate extending in another direction from the pivot, 90 a second plate having the low part of the cam path and mounted in variable positions on the body plate and a third plate having the high part of the cam path and independently mounted in variable position on 95 said body plate.

6. A cam mechanism including in combination a cylindrical rotating cam having a circular cam path, and actuated by said cam path, a cam having a pivot bearing, an 100 actuating arm extending in one direction from the pivot and cooperating with said cam path, and a flat body plate extending in another direction from the pivot, a second plate having the low part of the cam path 105 and mounted in variable positions on the body plate and a third plate having the high part of the cam path and independently mounted in variable positions on said body plate.

7. A cam comprising a cam body and a continuous cam path including a member carrying the high part of the cam and a second member carrying the low part of the cam, the two said members overlapping to 115 form a continuous trackway with which the element controlled by the cam is in continuous contact, and means for variably positioning and holding both said members on the cam body independently of each other to 120 vary the action of the cam.

8. A cam comprising a cam body and a continuous cam path including a member carrying the high part of the cam and a second member carrying the low part of the 125 cam, the two said members overlapping to form a continuous trackway with which the element controlled by the cam is in con-

tinuous contact, and independently operable devices for variably angularly positioning and holding both said members on the cam body independently of each other to vary the action of the cam.

9. A cam mechanism comprising a shaft, a cam body fixed thereto, a cam member mounted loosely on the shaft and carrying the high part of the cam, a second cam member mounted loosely on the shaft and carrying the low part of the cam, the two said members overlapping to form a continuous trackway with which the element controlled by the cam is in continuous contact, and means for variably positioning and holding both said members on the cam body independently of each other to vary the action of the cam.

10. A cam mechanism comprising a shaft, a cam body fixed thereto, a cam member mounted loosely on the shaft and carrying the high part of the cam, a second cam member mounted loosely on the shaft and carrying the low part of the cam, the two said members overlapping to form a continuous trackway with which the element controlled by the cam is in continuous contact, and means for variably angularly positioning and holding both said members on the cam body independently of each other to vary the action of the cam.

11. A cam comprising a slotted body plate, a slotted plate carrying one part of the cam track, a plate carrying a lower or higher part of the cam track, a clamping bolt passing through a slot in the body plate and threaded into the slotted cam track plate, and a clamping bolt passing through a slot in the cam body plate and in the slotted cam track plate and threaded into the other cam track plate.

12. A cam mechanism comprising a slotted body plate, a shaft to which the cam body is fixed, a slotted plate mounted loosely on the shaft and carrying one part of the cam track, a plate mounted loosely on the shaft and carrying a lower or higher part of the cam track, a clamping bolt passing through a slot in the body plate and threaded into the slotted cam track plate, and a clamping bolt passing through a slot in the cam body

plate and in the slotted cam track plate and threaded into the other cam track plate.

13. A cam comprising a slotted body plate, a slotted plate carrying one part of the cam track, a plate carrying a lower or higher part of the cam track, a clamping bolt passing through a slot in the body plate and threaded into the slotted cam track plate, and a clamping bolt passing through a slot in the cam body plate and in the slotted cam track plate and threaded into the other cam track plate, and a spacing block in the slot in the slotted cam track plate.

14. A cam comprising an oscillatable cam body and a continuous cam path including a member carrying the high part of the cam, a member carrying the low part of the cam, the two said members overlapping to form a continuous trackway with which the element controlled by the cam is in continuous contact, means for oscillating the cam body, and means for angularly variably positioning and holding both said members on the cam body independently of each other to vary the action of the cam.

15. A cam comprising an oscillatable cam body and a continuous cam path including a member carrying the high part of the cam and a member carrying the low part of the cam, means for angularly variably positioning and holding both said members on the cam body independently of each other to vary the action of the cam, a cooperating cam lever operated thereby, and means for varying the angular relation of said lever to the cam.

16. A cam comprising a cam body and a continuous cam path including a member carrying the high part of the cam and a member carrying the low part of the cam, and means for variably positioning and holding both said members on the cam body independently of each other to vary the action of the cam, a cooperating cam lever operated thereby, and means for varying the angular relation of said lever to the cam.

In testimony whereof, we have signed our names to this specification.

JOSEPH J. WALSER.
HARLAND FANKBONER.
